UNITED STATES PATENT OFFICE.

WILLARD C. BRINTON, OF NEW YORK, N. Y.

GRAPHIC CONTROL RECORD BOARD.

Application filed September 26, 1917. Serial No. 193,393.

To all whom it may concern:

Be it known that I, WILLARD C. BRINTON, a citizen of the United States of America, and a resident of New York, county and 5 State of New York, have invented certain new and useful Improvements in Graphic Control Record Boards, of which the following is a specification, reference being had to the accompanying drawings, forming a 10 part thereof.

My invention relates to methods and apparatus for graphically presenting facts and has special reference to charts or boards having adjustable means for producing 15 value curves and varying them as desired.

One object of my invention is to provide a simple means for representing values that shall be susceptible of ready adjustment to meet varying conditions.

20 A further object is to provide means adapted for representing both estimated and actual values, the estimated value representation being readily adjustable to make it dependent upon the most recent actual 25 value information.

Another object of my invention is to provide a method of making value curves on a wall board or the like, that shall be clean and accurate in construction and striking 30 and attractive in appearance.

Another object is to provide a variable record board comprising a plurality of adjustably supported strips or tickets which may be varied as to height or position to 35 represent values, the width of each strip representing, for example, a period of time.

In order that my invention may be thoroughly understood I will now proceed to describe the same in the following specification and then point out the novel features thereof in appended claims.

Referring to the drawings:

Figure 1 is a front elevation of a frame 45 or board constituting one embodiment of my invention.

Figure 2 is a sectional elevation of the same, drawn to a larger scale.

Figure 3 is a partial elevation illustrating 50 a modification of my invention.

Figure 4 is a sectional detail of the structure shown in Figure 3, and

Figures 5 and 6 are views corresponding

to Figures 3 and 4 showing still another modification of my invention. 55

Figure 7 is a front elevation of another record board which is arranged and constructed in accordance with my invention.

Figure 8 is a sectional elevation of a board shown in Figure 7. 60

Figure 9 is a partial front elevation drawn to a large scale to show the structure in detail and

Figure 10 is a sectional detail drawn to correspond with Figure 9. 65

Figures 11 and 12 correspond to Figure 10 and show slightly modified arrangements which may be employed instead of that shown in Figure 10.

The utility of the board shown in Figures 7 to 11 inclusive is further illustrated by Figures 13 and 14 which are front elevations of portions of the board. 70

Fig. 15 is a front elevation of an indicating pin head. 75

Referring first to Figures 1 and 2,—15 designates a board or mount of any suitable form which may preferably be provided with a frame such as 16, and is supported in a vertical plane. It may, for example, be conveniently secured to the vertical wall of a room or office. Appearing on the face of the board 15 near the lower right hand corner is an area designated 17 having coordinate lines 18 and 19. The coordinate lines may, if desired, extend over 80 the entire board but I prefer to leave a relatively wide margin at the left and at the top as illustrated, in order to leave room for the introduction of suitable scales, and columns 85 of figures as shown. 90

The base line 20 is divided by the coordinate lines 19 into time periods which may represent months and are numbered from 1 to 12 consecutively.

There is thus presented a coordinate sheet 100 having time set off in one direction and values to be plotted in the other direction. Assuming, for example, that the values represent the total value of sales made by a certain salesman, or by a company, the 105 value of sales for each month is indicated by the introduction of a pin or tack 21 into the board at the proper position on the coordinate lines 19. In order that the curve may start at the beginning of the year in-

stead of at the end of the first month, the first point on the curve such as the point 21, is placed according to the value of sales for the last month of the previous year. The 5 sales for the first month of the new year which is to be plotted are represented by the point 22 and so on, one pin being located on each of the lines up to the current month. The record in fact is intended to 10 be advanced month by month as the records are available.

In order that the sales may be represented by a curve instead of by the pins alone, I tie a suitable cord or thread 23 of some color 15 which contrasts in an attractive and striking manner, with the background of the mat, to the pin 21 and stretch it around the successive pins letting it hang downwardly from the last pin available, a weight 23^a 20 being attached to the end of the cord to keep it taut.

In addition to this curve other curves may be plotted on the same board, for example, a curve may be formed by adding each 25 month's sales to the preceding, thus getting the total sales represented. An estimated curve of this kind may be made at the beginning of the year from past performances of the same salesman in other years, or past 30 records of the company, as the case may be. The curve will be corrected each month in accordance with the actual sales value curve, the adjustment of the pins on the board being very readily accomplished.

35 The estimated curve and the actual total curve may be made independent, say, with strings or cords 31 and 32 of different colors. Weights 31^a and 32^a are attached to the respective cords. The estimated 40 curve will then be corrected each month judging from the record of the month, last past; thus, for example, the estimated curve may be as indicated at 24 at the beginning of the year, the actual curve may be found 45 to lie as indicated at 25; then the estimated curve should be revised as shown in broken lines at 26. Thus the estimated curve is always based upon the best information available.

50 As another example, one curve may indicate a schedule of goods to be manufactured and the other show the goods actually produced.

Attention is particularly directed to the 55 fact that the pins may be very readily changed in position and consequently the adjustment of the estimated curve for example, can be very readily made. At any time in the year a glance at the board indicates very simply and accurately the amount 60 of sales being brought in. Thus a very close line may be kept on the sales force or on the entire sales of a firm or company.

It is evident that instead of depending 65 upon sticking the pins into the board or mat

at the desired position the curve may be very closely approximated, particularly if the coordinate lines are close together, by having a series of small holes in the board as designated at 27 in Figure 3. These holes 70 are at the intersection of the coordinates and are adapted to receive specially fitted plugs or pins 28.

A series of buttons or pins are located at the bottom of the board opposite the 75 vertical coordinates in convenient location to have the cord wound over them to keep the weight above the floor and out of the way when the points of the curve are relatively low, as shown in Figure 3.

80 As the points always fall on the coordinates 19 representing the close of the time period, the board may be formed as shown in Figure 5, with slots or grooves 19^a, extending at right angles to the coordinates 18 and taking the place of the coordinates 19. These slots may be enlarged at the bottom as shown in Figure 6, and spring clips 29 which fit closely in the slots utilized therein. The clips may of course be slid along 85 the slots to any desired position and the strings or cords for indicating the curves attached to them.

To call the attention of the management 90 or anyone interested, to the fact that the actual curve has fallen below the schedule or estimated curve, as for example, in Figure 1, a large arrow, flag or other signal may be employed. If the curve is below the schedule, the red arrow or signal may be employed for example, and if it is above a blue or green arrow may be employed. The arrow will usually be cut out of celluloid and adapted to be fastened to the board at 95 any convenient position.

100 Referring now to Figures 7 to 11 inclusive, the structure here shown comprises a board 40 having a sheet 41 of some tough yielding material, such as celluloid, in which a large number of cuts or slots 42 are made. These cuts or slots lie in parallel coordinate lines which extend horizontally of the board 105 on which the sheet 41 is mounted. I prefer to reinforce the sheet and to hold it firmly in position particularly at the ends of the slots, by means of screws or tacks 43 which extend through the sheet 41 and have washers 44 which may overhang the ends of the slots, but in any event produce a pressure 110 between the slotted sheet and the back and provide sufficient friction to hold the tickets in position as adjusted.

115 The washers may be omitted if screws are employed because the pressure can be easily 120 adjusted by turning the screws in or out to give the friction desired. If tacks or nails are employed, resilient washers are desirable and I prefer to utilize a spring washer 45 as shown in Figure 11 or a felt washer 46 as 125 shown in Figure 12. Spring fingers press- 130

ing the slotted sheet against the backing may be substituted for the washers if desired.

5 Strips or tickets of celluloid or the like are provided and are fitted with considerable friction into the slots 42. They are set into the slots and allowed to extend above the slots to a height which represents a definite value on the scale shown at the left 10 in Figure 7 for example.

The tickets or strips which are placed in the slots may be formed of celluloid with sand-blasted surfaces or of cardboard or like material, so that the value of figures may be 15 written directly thereon. By this means the position of the ticket indicates a value and the ticket may constitute a memorandum of the value as written on its face. When a ticket is changed in position the value figures 20 are easily erased and new ones put on. This is particularly advantageous for limit tickets, as hereinafter described, which indicate the capacity of a mill for example.

25 The surface plate of the board may also be suitable for having memoranda written thereon.

In an arrangement like that shown in Figures 3 and 4, the pins or plugs may have flat sand-blasted celluloid heads on which the 30 value corresponding to its position is inscribed. A pin of this kind is shown in Figure 15.

35 The board may be utilized for various purposes and is well adapted to be utilized for keeping a continuous record of the orders booked for delivery at any definite time. Assuming for example, that a mill manufacturing different widths of cloth has a group 40 of salesmen in the field. The salesmen are continually telegraphing in orders for cloth for delivery at different times,—so many yards for example in January; so many in February, and so many in March, etc. By raising the tickets or slips 47 to correspond 45 to the orders in each month of the year, it may be seen at a glance how near the capacity of the mill is sold, for any given month. The capacity of the mill may for instance be marked by a limit strip or ticket of a different color as shown at 48 in Figure 13, and one or more narrower strips 49 and 52 representing the orders, raised gradually over the limit strip. By this means it may be seen 50 at a glance just what the condition of the orders is and it is possible to operate several sets of tickets at once, the tickets having different colors and representing each a different grade or width of material.

55 The tickets may either be built up to make 60 a continuous strip from a zero line which is designated 50 so that their exposed length as well as the height of the top represents the aggregate amount of the orders, or only the top line of each ticket may be depended

upon to indicate the amount of the order as 65 read on the scale at the left.

In the latter case only a small part of each ticket will be visible, as shown near the top of the board in Figure 7, and the tops of the tickets will produce a curve which is designated 70 55. There will thus obviously be room for several curves on the board at the same time. It is not essential that all curves be plotted from the same zero line, one or more of the scales being preferably started from 75 an intermediate zero line such as 56, so as to keep the curves from conflicting.

The zero line which is intermediate the board may be clearly designated by the use of a transverse cord or tape 64 having weights 80 65 hung at its respective ends.

The current month or some other predetermined special time may be conveniently designated by means of cords or tapes suspended from the top of the board and extending at right angles to the base line. A tape 57 having a weight 58 to keep it taut is attached by a pin or tack 59 and a tape 60 having a weight 61 is suspended from a pin or tack 62, one being located at one side and 90 95 the other of the current month's tickets.

Attention is directed to the fact that the board may be photographed, each day or each week for example, to give a permanent 95 record of the condition of the orders from time to time.

When the wide and narrow strips or tickets are used together as shown in Figures 13 and 14, care must be taken to select 100 contrasting colors which will photograph to differentiate from each other.

If the background photographs light and the limit ticket dark, then if the sale ticket shows light it will contrast properly unless 105 the factory is oversold and the sales ticket is raised above the limit. In this case the sales ticket should have a dark margin line as shown at 53 or a light margin as indicated at 54.

110 The board instead of being used in a vertical position may be laid on a table or utilized in any suitable position and springs substituted if necessary for the weights to hold the cords or tapes taut, or the cords 115 may extend over the edge of the table and have weights attached to them so that they are drawn taut.

While I prefer to utilize cords which extend between the pins to clearly indicate the 120 curve, this is not essential and the pins alone may be utilized in which case it is desirable to increase the number of pins by locating more points on the curve.

Instead of having the cord fastened at 125 zero and extending between the pins or attachments so that it depends from the last one, the weight may be attached to the op-

posite end of the cord or the cord wound on a spring drum or the like at the zero point from which it is pulled out as each additional point is added to the curve. In this 5 case a ring may conveniently be attached to the outer end of the cord so that it can be fastened radially to the last pin.

The strings may be made of different colors in order that the curves may be readily 10 contrasted or pins of one color may be used for one curve and those of another color for another curve.

The back or surface member into which the tickets or pins are to be inserted may 15 be in the form of a blackboard, or smooth surface member on which areas may be readily shaded by chalk, crayon or the like. The utility of the shaded areas is illustrated 20 in Figure 5 where two curves for example, are shown, one indicating the income or bills receivable, the other the outgo or bills payable. The difference between the curves indicates the estimated balance or deficit and if the area represents a deficit it may be 25 shaded in one color and the areas represent a balance shaded in another color.

While I have shown the strings extending between a large number of pins to represent a curve, certain mathematical computation 30 curves may be made by the use of a single pin at the zero line and another pin adjustably located at a distance from the zero with a cord stretched from the zero over the pin.

In other words, my invention is not limited 35 to a large number of pins and curves may be designated by as few as two pins.

The structure shown and described may of course be utilized in a wide variety of ways, and while I have chosen simple illustrations 40 in order that the operation of the device may be clear, I intend only such limitations as are imposed by the appended claims.

What I claim is:

1. A graphic record apparatus comprising 45 a board having a surface plate provided with a plurality of slots arranged in substantially parallel coordinate lines, substantially flat tickets or strips adapted to be mounted in the slots and to project predetermined amounts therefrom to enable the top of each ticket or strip to indicate a value.

2. A graphic record apparatus comprising 50 a support, a surface plate thereon having a plurality of slots arranged in substantially parallel coordinate lines, means for pressing the surface plate against the support near the ends of the slots, and tickets or strips adapted to be inserted in the slots and extending above the slots to represent 55 values.

3. A graphic record apparatus comprising 60 a board having means corresponding in position to coordinate lines for supporting tickets or cards in various positions thereon, said tickets or cards being adapted to

have value numbers written thereon, whereby not only their position on the board but also the legend inscribed thereon designate their value.

4. A graphic record apparatus comprising 70 a board having means corresponding in position to coordinate lines for supporting celluloid tickets in various positions thereon, said celluloid tickets having roughened surfaces adapted to have figures inscribed thereon to represent their values corresponding to the positions which they occupy on the board.

5. A graphic record apparatus comprising 80 a board having coordinate lines, and means adapted to be adjustably mounted on the board to produce an adjustable curve.

6. A graphic record apparatus comprising 85 a board having coordinate lines, and means adapted to be adjustably mounted on the board to produce an adjustable curve, said means being adapted to have figures inscribed thereon to designate their values corresponding to their positions on the board.

7. A graphic record apparatus comprising 90 a board having a plurality of parallel slots arranged in parallel coordinate lines on the board, and adjustable means adapted to be mounted in the slots to represent sections of the curve, and means for frictionally holding the adjustable means.

8. A graphic record apparatus comprising 95 a board having a plurality of parallel slots together forming coordinate lines on the board, and tickets adjustably mounted in the slots and adapted to have value numbers inscribed on the exposed end thereof and arranged to represent sections of a curve.

9. A graphic record apparatus comprising 100 a board having a plurality of parallel slots together forming coordinate lines on the board, tickets adjustably mounted in the slots, and means for frictionally holding the tickets in adjusted positions to represent the sections of a curve.

10. A graphic record apparatus comprising 105 a board having a plurality of parallel slots arranged in parallel coordinate lines on the board, tickets adjustably mounted in the slots, and adjustable means for frictionally holding the tickets to represent sections of a curve.

11. A graphic record apparatus comprising 110 a slotted board adapted to receive a plurality of tickets, the positions of the tickets determining a curve and cords or tapes extending transversely of the slots and between groups thereof to emphasize a particular portion of the curve.

12. A graphic record apparatus comprising 115 a board having a plurality of slots laid out in coordinate lines, means adjustably mounted in the slots for determining sections of the curve, and means for emphasizing one of the sections of the curve that con- 120

sists in stretching cords or tapes on the respective sides of the section to be emphasized.

13. A graphic record apparatus comprising a board having a plurality of slots laid out in coordinate lines and tickets adjustably mounted in the slots adapted to represent a period of time such as one month and their position or height representing a value for that time, and means for emphasizing one period of time on the board as for example, a current month.

14. A graphic record apparatus comprising a board having a plurality of slots laid out in coordinate lines and tickets adjustably mounted in the slots adapted to represent a period of time such as one month and their position or height representing a value for that time, and means for emphasizing one period of time on the board as for example, a current month that consists in stretching cords or tapes at right angles to the slots and on respective sides of the current month's ticket.

25. 15. A graphic record apparatus comprising a board having a surface member of one color in which are a plurality of slots, tickets adapted to be adjustably mounted in the slots, limit tickets of a different color mounted in the slots and adjustable curve section tickets mounted in the same slots and adapted to be adjusted independently of the limit tickets to represent sections of a curve.

35. 16. A graphic record apparatus comprising a board having a surface member of one color in which are a plurality of slots, tickets adapted to be adjustably mounted in the slots, limit tickets of a different color mounted in the same slots and adapted to be adjusted independently of the limit tickets, the adjustable tickets having a body to contrast particularly with the limit ticket, and a margin adapted to contrast with the surface member whereby the outline of the ticket will photograph when the adjustable ticket extends beyond the limit ticket.

50. 17. A graphic record apparatus comprising a board having a surface member with slots therein, and a plurality of tickets adjustably mounted in each slot whereby said tickets are adapted to represent sections of a curve.

55. 18. A graphic record apparatus comprising a board having a plurality of slots laid out in coordinate lines, tickets adjustably supported in said slots and arranged to represent sections of a curve, and means for stretching a cord or tape in alignment with one set of slots to designate a base line intermediate the board.

60. 19. A graphic record apparatus comprising means for representing the curve on the board, and a signal adapted to be removably

mounted on the board to call attention to a particular part of the curve.

20. A graphic record apparatus comprising a board having coordinate lines thereon, a zero point, an adjustable member and a cord extending between the zero point and the adjustable member and having means for holding it taut.

21. A graphic record apparatus comprising a board having coordinate lines thereon, a zero point, an adjustable member for indicating different values on said lines, and a cord extending between the zero point and the adjustable member and having a weight secured thereto for holding it taut.

22. A graphic record apparatus comprising a board having coordinate lines thereon, a zero point, adjustable means for indicating different values on said lines, a cord extending from the zero around said adjustable means and means for holding said cord taut.

23. A graphic record apparatus comprising a board having coordinate lines thereon, a zero point, adjustable pins for indicating different values on said lines, a cord extending from the zero around said adjustable pins and means for holding said cord taut.

24. A graphic record apparatus comprising a board having coordinate lines thereon, a zero point, adjustable means for indicating different values on said lines, a cord extending from the zero around said adjustable means and a weight secured to the cord for holding said cord taut.

25. A graphic record apparatus comprising a board having a surface plate provided with a plurality of slots arranged in substantially parallel coordinate lines, substantially flat strips adapted to be adjustably mounted in the slots and to project to a desired extent therefrom to enable the exposed portion of each strip to indicate a value.

26. A graphic record apparatus comprising a board having a surface plate provided with means arranged in substantially parallel coordinate lines for supporting strips, substantially flat strips adapted to be adjustably supported by said means and to project to a desired extent therefrom to enable the exposed portion of each strip to indicate a value.

27. A graphic record apparatus comprising a board having a surface plate provided with a plurality of substantially parallel slots, strips adapted to be adjustably mounted in said slots and to project to a desired extent therefrom to enable the end of the strip to indicate a value.

In witness whereof, I have hereunto set my hand this 12 day of September, 1917.

WILLARD C. BRINTON.
